BASKET GRATE FOR STOVES

Samuel A. Burnett, Ottumwa, Iowa

Application October 27, 1943, Serial No. 507,848

2 Claims. (Cl. 126—170)

This invention relates to a basket grate for stoves.

An object of the invention is the construction of a comparatively simple and efficient basket grate which obviates the use of stove linings, and at the same time produces a far better structure than a lined stove, because of greater heat radiation created by a stove in which my invention is used.

Another object of the invention is the construction of a basket grate that is efficient, comparatively inexpensive to manufacture, and which can be easily placed in a stove body, and manipulated when in position.

With the foregoing and other objects in view, my invention comprises certain novel constructions, combinations, and arrangements of parts as will be hereinafter fully described, illustrated in the accompanying drawing, and more particularly pointed out in the appended claims.

In the drawing:

Figure 1 is a vertical central, sectional view of my basket grate shown in a stove body.

Figure 2 is a horizontal, sectional view taken on line 2—2, Figure 1, and looking in the direction of the arrows.

Figure 3 is a horizontal sectional view taken on line 3—3, Figure 1, and looking in the direction of the arrows.

Figure 4 is a vertical sectional view taken on line 4—4, Figure 1.

Figure 5 is a fragmentary sectional view of the slotted basket and the grate, showing the peculiar manner or method of placing the grate in position upon the slotted basket.

Figure 6 is a view in elevation of the grate showing one end of its housing and the spur thereof.

Referring to the drawing by numerals, I designate a stove of any preferred construction; the stove 1 is provided with a continuous horizontal annular flange 2 for supporting my basket grate.

The basket grate comprises a slotted basket 3 which is provided upon its upper annular rim 4 with a plurality of outwardly extending horizontal lugs 5. When the basket grate is in the stove 1 these lugs 5 rest upon the top of the annular flange 2, thereby spacing the basket 3 from the inner walls of the stove 1. The basket grate 3 is provided on its lower end with an inwardly extending continuous annular flange 6. This flange 6 is provided on its inner edge with an inwardly extending bevelled face 7 for the purpose hereinafter described.

The grate 8 comprises a flat body 9 having an

integral broad depending housing 10. This housing extends substantially the entire width of the body 9 and is provided at both ends with vertical bearing faces 11; each bearing face 11 is curved to conform to the curvature of the face 7 of flange 6. These bearing faces 11 are adapted to slidably engage the continuous annular flange 6 of the basket 3. On one end of housing 10 and below its curved bearing 11 (Fig. 6) is a tapering spur 12. Spur 12 is normally under the continuous annular flange 6, to assist in holding the grate in position upon the basket. The broad elongated housing 10 has at one end, opposite to spur 12, a broad socket 13 for receiving the broad inner end of shaker 14. The shaker 14 is broader at 15 than socket 13 whereby the shaker when inserted at its inner end into socket 13, has portions of the broad part 15 engaging the socketed end of housing 10, Fig. 3.

20 When inserting the grate 8 into position upon the basket 3, the grate is placed down in the basket in the manner illustrated in Figure 5. By reason of the bevelled inner edge 7 of flange 6 the spur 12 is permitted to pass by and under the flange 6 which it would otherwise be impossible to do if the flange 6 was not bevelled in this novel manner. Further, the spacing of the spur 12 below the curved bearing 11 on housing 10 gives sufficient room for the spur to be under flange 6 and the flat body 9 to be above said flange. When the spur 12 has been positioned under flange 6, the flat body 9 will be resting upon the annular flange 6, whereupon the broad inner end of shaker 14 can be inserted in socket 13, resulting in the grate being locked upon the basket against displacement. The grate can be easily "shaken" by swinging the shaker 14, resulting in the grate being rotated upon the flange 6 of the basket 3.

40 It is to be noted that the spur 12 is bevelled downwardly at 12a upon its upper face and is not bevelled upon its lower face 12b, thereby making more clearance for allowing insertion of the spur under flange 6, as will be seen upon first studying Figure 5 and then Figure 1.

45 It is to be noted that the greater portion of the slotted basket does not touch the fire bowl, which prevents burning of the bowl and also saves the cost of stove linings. Further, through the slotted basket the stove radiates a steady toasting heat that is not obtainable with a lining packed with fine ashes. By using my invention extra heat is gained as the entire body of the stoves gives great radiation, which is not true of a stove that has a lining. Ashes fall freely through the slots of the

basket, giving a free burning result because the fire burns freer by reason of better draft, etc.

While I have described the preferred embodiment of my invention and illustrated the same in the accompanying drawing, certain minor changes or alterations may appear to one skilled in the art to which this invention relates, during the extensive manufacture of the same, and I, therefore, reserve the right to make such alterations or changes as shall fairly fall within the scope of the appended claims.

What I claim is:

1. In a device of the class described, the combination of a basket provided at its lower edge with a continuous inwardly directed solid annular flange, said flange being inwardly and upwardly inclined or bevelled on its inner face, a grate resting on said solid annular flange, said grate being provided with a spur spaced below the upper surfaces of the grate, said spur having its top downwardly and outwardly bevelled, whereby said spur can slide along said bevelled portion of said flange and be positioned under said flange, and a shaker on said grate and co-

acting with the under-side of said continuous annular flange to hold the grate in position on said flange.

2. In a device of the class described, the combination of a basket provided at its lower edge with a continuous inwardly directed solid annular flange, said flange being inwardly and upwardly inclined or bevelled at its inner face, a grate resting on said solid annular flange, said grate being provided with a depending housing, said housing having vertical bearing faces on its ends, said bearing faces conforming to the curvature of the annular flange and its bevelled portion, said housing having a bevelled spur spaced below the bearing faces and a shaker-receiving socket on its ends below said vertical bearing faces, said bevelled spur being adapted to slide along and under said bevelled portion of said annular flange and be positioned thereby under said flange, and a shaker in said shaker-receiving socket cooperating with the underside of said annular flange to hold the grate in position on said flange.

SAMUEL A. BURNETT.
